DESIGN FOR A LAWN SPRINKLER

Fred O. Weirich, Chicago, Ill., assignor to Chicago Flexible Shaft Company, Chicago, Ill., a corporation of Illinois

Application August 23, 1940, Serial No. 94,587

Term of patent 14 years

To all whom it may concern:

Be it known that I, Fred O. Weirich, a citizen of the United States, residing at Chicago, in the county of Cook and State of Illinois, have invented a new, original, and ornamental Design for a Lawn Sprinkler, of which the following is a specification, reference being had to the accompanying drawing, forming part thereof.

In the drawing:

Fig. 1 is a side elevation of a lawn sprinkler embodying my invention;

Fig. 2 is a side view of the lawn sprinkler looking at the right hand side of Fig. 1;

Fig. 3 is a plan view of the lawn sprinkler; and
Fig. 4 is a fragmentary vertical section through the base taken on a radial plane.

I claim:

The ornamental design for a lawn sprinkler, substantially as shown.

FRED O. WEIRICH.
